AUTOMOBILE INSTRUMENT PANEL

Oscar Wilfred Grunau, Coventry, England, assignor to Awson Motor Carriage Company, Ltd., Coventry, England, a company of Great Britain

Filed May 17, 1965, Ser. No. 85,316

Term of patent 3½ years

(Cl. D14—6)

FIGURES 3 and 4 respectively are top and bottom plan views thereof;

I claim:

The ornamental design for an automobile instrument panel, as shown.
